UNITED STATES PATENT OFFICE.

HENRY HITCHCOCK, OF LYONS, MICHIGAN.

SULKY REVOLVING RAKE.

SPECIFICATION forming part of Letters Patent No. 241,013, dated May 3, 1881.

Application filed January 3, 1881. (No model.)

To all whom it may concern:

Be it known that I, HENRY HITCHCOCK, of Lyons, in the county of Ionia and State of Michigan, have invented an Improvement in Sulky Revolving Rakes, of which the following is a specification.

My invention relates to improvements in sulky revolving rakes; and it consists in the peculiar construction and arrangement of the parts, as hereinafter more fully set forth.

Figure 1 is a vertical longitudinal section on the line y y in Fig. 2. Fig. 2 is a plan of a part of the device, both sides of the device from the center being alike. Fig. 3 is a perspective view of one of my sliding boxes. Fig. 4 is a side elevation of the same, showing cam-head on rake-shaft. Fig. 5 is a detached perspective view of the cam-head on rake-shaft. Fig. 6 is a cross-section through the rake-head, showing method of securing the spring-teeth thereto.

In the accompanying drawings, which form a part of this specification, A is a frame which carries the operating parts of the machine. This frame is pivotally secured, by eyebolts a , 25 hinges, or other suitable devices, to the frame B, to which the axle C is rigidly secured, the former frame resting prone upon the latter and extending to the rear, as shown in Fig. 1.

D are the hounds, to which the draft-tongue (not shown) is secured.

E are the traction-wheels, journaled in any of the known ways to the axle at each end thereof.

F are pulleys, secured and adapted to rotate with the traction-wheels. Belts G convey motion from these pulleys to the pulleys H, one of which is secured to each end of the rake-head I. Each end of this rake-head is journaled in a box, J. These boxes are composed 35 of the bed-box b and the cap e , hinged at one end to the bed-box, as shown in Fig. 3, and when the parts are in place the cap is held rigidly by the stud d , secured to the bed-box and passing up through cap, where a key, e , passing 40 through a slot in the stud-bolt, locks the two parts of the box together. These boxes slide in ways K secured to the top of the rearward-projecting ends of the frame A. A swivel, h , is pivotally secured to the front end of each 45 of these boxes, and to the swivel is connected a rod, i , by means of two nuts, k k' , in such

manner that the connection may be adjusted as to its length, and the opposite end of the rod is connected to the crank l on the end of the rock-shaft L, which is journaled in suitable 55 bearings m on top of the frame A.

A foot-lever, M, within easy reach of the operator on the seat N, and secured to the rock-shaft, when depressed, as shown in Fig. 1, 60 forces the boxes in the slides to the rear, thereby tightening the belts G and compelling them to communicate a rotary motion to the rake-head. When the pressure is removed from the lever the spring n compels the lever to assume the position shown in dotted lines in Fig. 1, 65 thus retracting the boxes in the slides, by which means the belts are slackened and the rotation of the rake-head is stopped. The bottom edge of the boxes J is provided with a ratchet, o , and a spring-pawl, p , engages with the teeth 70 of this ratchet, being compelled thereto by the spring q . A bell-crank is pivotally secured to the frame A, the shorter arm r of said crank being pivoted to the link s , which, in turn, is pivoted to the bed-box b , while the longer arm 75 t hangs free, with its free end terminating in an outwardly-projecting flange, u .

O is a cam-wheel, secured near one end of the rake-head, and its hook v is designed to engage with the flange u of the bell-crank. 80 The cam-wheel is also provided with a cam-flange, w , which is designed, when the rake-head is rotated, to engage with and depress the spring-pawl p and free its engagement with the ratchet.

In Fig. 2 the rake-head is shown in its position after the teeth P have deposited the windrow and the rake has commenced its rotation, which brings the rear side of the rake-head to the top. To secure the teeth in place a series 90 of hook-shaped bolts, R, are driven at regular intervals through the head. The wire forming the teeth is bent around the bolt between the nut S and the face of the head; thence it passes around the head and through the hook 95 of the bolt, as shown in Figs. 1 and 6, and thence under the beam toward the rear, and terminates in the proper curve for its purposes.

It will be noticed in Fig. 6 that the hook of the bolt will prevent any lateral displacement 100 of the tooth, while at the same time it will allow the teeth to spring or have a fore-and-aft

movement between the end of the hook and the side of the head, and by this means a greater flexibility to the teeth is obtained and the liability of breakage is greatly diminished.

5 T is a caster-wheel swiveled to the curved standard V, which passes forward over the axle C and beneath the frame A, and its forward end is pivoted to the under side of said frame at x.

W is a cam-lever pivoted within the frame 10 A and projecting through the slot y in the same to engage with the standard V. By drawing this lever to the rear the cam raises the frame A, and, of course, the rake, and thereby the operator is enabled to control the height 15 of the rake-teeth from the ground at will.

The caster-wheel also serves to keep the device level and steady when one of the traction-wheels is running in a "dead furrow."

In practice, when the rake is in operation 20 the hook v of the cam-wheel O is engaged with the flange u of the crank-arm, to prevent any rotation of the rake-head, and the boxes J are retracted in their slides toward the front of the machine, with the lever M in the position shown in dotted lines in Fig. 1. As the teeth become 25 filled with hay and the driver wishes to "dump," he depresses the lever M, which projects the boxes J to the rear, where the spring-pawl p secures them by engaging with the ratchet. 30 The same movement of the lever, in addition, disengages the flange u from the hook v, and the belts being tightened the motion of the pulleys F is communicated to the rake-head, and the rake commences its rotation rearward, up- 35 ward, and forward until it has reached a point forward of the center of gravity, when the flange-cam w will depress the spring-pawl and release the boxes J. The lever M being relieved from pressure, the spring n compels it 40 to assume its original position, thereby retracting the boxes J, and throwing the arm t of the bell-crank into position to engage with the hook v, thus slackening the belt and causing its action in revolving the rake-head to cease, 45 the further entire revolution of the rake-head being completed by the gravity of the rake-teeth, which fall rapidly to the ground. By this construction the rake-head is partially re- 50 volved by means of the devices above described, the latter part of the revolution being effected independently of the motion of the driving-

wheel by the weight of the teeth, which will cause the rake to revolve with more rapidity than when connected to the driving-gearing, especially when the driving-wheel is turning a 55 corner and not revolving, or revolving but slowly.

What I claim as my invention is—

1. The combination, with the traction-wheels E, having the belt-pulleys F secured thereto, 60 and rake-head I, having teeth arranged on one side only of said head, and carrying the belt-pulleys H, of the belts G, sliding boxes J, rock-shaft L, having end cranks, l, lever M, spring n, and connecting-rods i, substantially as de- 65 scribed.

2. The combination, with the sliding boxes J, carrying the bearings of the rake-head and ways K, of the rock-shaft L, having the end cranks, l, lever M, spring n, and connecting- 70 rods i, substantially as described, and for the purpose set forth.

3. As a means of securing the sliding boxes J of a sulky spring-tooth revolving rake in position when projected, the ratchet o, spring- 75 pawl p, and spring q, substantially as described.

4. As a means of releasing the projected sliding boxes J of a sulky spring-tooth revolving rake, the flange-cam w, upon the cam-wheel O, in combination with the ratchet o, spring-pawl 80 p, and spring q, substantially as set forth.

5. In a sulky spring-tooth revolving rake, and in combination with the rake-head and sliding boxes, the cam-wheel O, provided with hook-cam v, the bell-crank, and flange-stop u 85 thereon, substantially as and for the purposes specified.

6. The combination, with the rake-head I, and screw-bolt R driven through said head and provided with a hook on its forward end and a 90 nut on its rear end, of the spring-tooth P, pro- vided with a loop at its upper end, passing over the rear end of the bolt, and secured to the rake-head and bolt by the nut, and thence passing through the hook in the loop, substan- 95 tially as described, and for the purpose set forth.

HENRY HITCHCOCK.
